**GAS FLAME COMBINED COVER PLATE
AND SIMMERER**

Lena L. Troutman, 418 W. Monroe St.,
Salisbury, N.C. 28144

Filed Aug. 16, 1968, Ser. No. 13,161

Term of patent 14 years

Int. Cl. D7—04

U.S. Cl. D81—25

FIGURE 1 is a top plan view of a gas flame combined cover plate and simmerer;

FIG. 2 is a side elevational view thereof;

FIG. 3 is a bottom plan view;

FIG. 4 is a cross-sectional view as viewed on line 4—4 of FIG. 1.

I claim:

The ornamental design for a gas flame combined cover plate and simmerer, substantially as shown.
